UNITED STATES PATENT OFFICE.

JAMES O'DONNELL, OF ST. LOUIS, MISSOURI.

IMPROVEMENT IN HATS.

Specification forming part of Letters Patent No. **138,430**, dated April 29, 1873; application filed October 21, 1872.

To all whom it may concern:

Be it known that I, JAMES O'DONNELL, of the city and county of St. Louis and State of Missouri, have invented certain Improvements in Ventilated Hats, of which the following is a specification:

This invention consists in forming inside the crown of the hat an annular chamber, into which air passes through a series of openings in the brim, the air escaping from the hat through openings in the crown. The annular chamber has free communication over the "sweat-band" with the interior of the hat to allow the air to circulate around and cool the head.

In the drawing, Figure 1 is a bottom perspective view. Fig. 2 is a sectional elevation.

A is the brim, which is turned up in a flange at *a* to give support to the sweat-band B. C is the crown, which is connected to the brim at a distance from the flange *a* so as to leave an annular space, D, between them, whose bottom is formed by the brim, and which is open at top to the inside of the hat. *d* are open-

ings in the brim, through which air from the outside enters the annular space or chamber D; and *c* are openings or holes in the crown C, through which the air escapes from the inside of the hat. The annular diaphragm B', extending from the upturned part *a* of the brim to the crown-lining E, is perforated or formed of any suitable open-webbed material so as to allow the air free circulation around the head of the wearer to carry off the perspiration and heat therefrom.

I claim as my invention—

The hat herein described having the brim A turned up in a flange, *a*, and the crown C attached to the brim outside of and at a distance from said flange so as to form the chamber D, and having the perforated or open-webbed inner casing B' attached inside of said flange *a* and between it and the sweat-band B, as shown and described.

JAMES O'DONNELL.
